S. A. JONES,
RAIL JOINT,
APPLICATION FILED FEB. 16, 1920.

Patented July 13, 1920.

FIG-1.

FIG-3.

FIG-2.

INVENTOR
SLOANE A. JONES.

BY *R. B. Huston*

ATTORNEY

UNITED STATES PATENT OFFICE.

SLONE A. JONES, OF SPRINGVILLE, ALABAMA.

RAIL-JOINT.

1,346,656.

Specification of Letters Patent. Patented July 13, 1920.

Application filed February 16, 1920. Serial No. 359,194.

To all whom it may concern:

Be it known that I, SLONE A. JONES, a citizen of the United States of America, residing at Springville, in the county of St. 5 Clair and State of Alabama, have invented certain new and useful Improvements in Rail-Joints, of which the following is a specification.

My invention relates to rail joints and has 10 for its object to provide a joint which comprises a relatively small number of parts and which will afford the maximum strength for the joint.

According to my invention, each joint 15 comprises an integral splice bar section having a relatively narrow cross member adapted to lie between the ties and under the rail joint, the other splice bar being provided near its ends with bracing extensions which 20 are spiked to the ties. Between the ties I provide two transverse U-bolts, one on each side of the joint which extend crosswise under the bottom cross member and serve to tie the two splice bars together and afford 25 the maximum supporting strength in the joint for the rail ends. The extension braces referred to are of special advantage in bracing the joint about curves and on tangents.

My invention also comprises the novel 30 details of construction and arrangements of parts, which in their preferred embodiment only are illustrated in the accompanying drawings which form a part of this specification, and in which:-

Figure 1 is a perspective view of the inside joint member with the rail dotted in.

Fig. 2 is a plan view of the members of the joint assembled.

Fig. 3 is a cross sectional view taken on the 40 line 3—3 of Fig. 2.

Similar reference numerals refer to similar parts throughout the drawings.

I have illustrated my invention in its simplest embodiment and as shown in the 45 drawings it comprises two main joint members A and B. The member A comprises a fish-plate section C adapted to extend sufficiently on each side of the joint so that its base D will overlie the cross ties on each 50 side of the joint and between the cross ties this joint section has an integral transverse cross member E forming a joint brace which in width fits closely between the ties but does not overlie the ties. In thickness this 55 cross member substantially corresponds with

the fish-plate A, the base of which has double thickness where the cross member joins therewith. The cross member in itself is a substantial support for the abutting ends F and G of the main track rails which 60 meet midway over this brace E. The brace E in length is sufficient to come flush with the outer edge of the base flange H of the joint section B and in order to more securely couple the joint sections together, and especially to brace and support the extension E, I provide a pair of U-bolts I, the body portions of which fit flush against the under face of the brace E and the upturned ends of each bolt are threaded and inserted 65 through the base flange D on the one side and through the brace E and base flange H on the other side. These U-bolt members are preferably adjacent to the cross ties, thus bringing them near the point of support from the cross tie and tying the whole 70 joint together in a most rigid and effective manner while at the same time providing the joint supporting brace E with that reinforcement which is necessary to support it 75 under all reasonable load strains that may come on it in service.

To increase the usefulness of the joint and to adapt it to brace the track where needed, I provide the member B with brace 80 extensions J, which are of substantial length and sufficient in width so that each can receive a number of spikes K. As shown I have used three spikes in each brace extension and in practice I will probably give 85 these braces a length of about 6", though this may be varied as conditions may require.

In assembling the apparatus it is to be noted that it is unnecessary to lift the rails 90 from the ties, the joint being applied merely by slipping the fish-plate members A and B against the rail from each side and fitting the joint brace E between the adjacent ties, after which the fish-plates of the joint 95 members are bolted together through the rails by the customary bolts L and the U-bolt braces I are then inserted and bolted in place and the joint is ready for service. It will be noted that should all of the bolts 100 L be sheared or stripped the U-bolts I would still sufficiently hold the joint to prevent its 105 opening up and causing a derailment.

This invention is not intended to be restricted in scope to the specific embodiments 110

shown, but contemplates such modifications as come within the spirit and scope of the claims.

What I claim as new and desire to secure by Letters Patent, is:—

1. A joint for rails comprising two joint members, one joint member comprising a splice bar for one side of the rails having a transverse integral base extension adapted 10 to underlie and support the joint between the rails, and the other joint member comprising a splice bar section having a base flange adapted to overlie the free end of said transverse joint support, and transverse U- 15 bolts connecting the two joint members on each side of the rail joint and adapted to brace said joint support, substantially as described.
2. A joint for rails comprising two joint members, one joint member comprising a splice bar for one side of the rails and a transverse integral base extension adapted 20 to underlie and support the rail joint, the other joint member comprising a splice bar for the other side of the rails having a base flange adapted to overlie the free end of 25 said base extension, and transverse U-bolts connecting the two joint members on each side of the rail joint, said U-bolts at one end 30 being bolted through the base flange of the splice bar where it is joined to the base extension and the base flange of the other

joint member to tie the joints together and form supports for said base extension on each side of the rail joint.

35

3. A rail joint comprising an inside member having a fish-plate portion elongated sufficiently to rest on adjoining ties and having an integral transverse joint supporting extension adapted to fit in between adjacent 40 cross ties, an outside member comprising a fish-plate portion also adapted to rest on adjoining cross ties and having the middle part of its base overlying the free end of said transverse extension of the inside member, said outside member having above its supporting cross ties substantially elongated brace portions with apertures to receive securing spikes, and a plurality of U- 45 bolts having straight bodies and right angled threaded ends adapted to be inserted upwardly at one side through the base extension of the inside joint member and at the other side through the overlying base of the outside joint member and said base extension on the inside joint member thereby 50 tying the two joint members together and bracing said extension on each side of the rail joint.
